UNITED STATES PATENT OFFICE.

SOLOMON FINK STEVER, OF FAIRFIELD, IOWA.

RAILWAY-RAIL JOINT.

No. 830,020.

Specification of Letters Patent.

Patented Sept. 4, 1906.

Application filed September 18, 1905. Serial No. 278,839.

To all whom it may concern:

Be it known that I, SOLOMON FINK STEVER, a citizen of the United States, residing at Fairfield, in the county of Jefferson and State of Iowa, have invented certain new and useful Improvements in Railway-Rail Joints, of which the following is a specification.

My invention relates to an improved railway-rail joint; and it consists in the constructions, combinations, and arrangements herein described and claimed.

The object of my invention is to provide a suspended joint for railway-rails which will clamp the inclosed rail ends against vertical oscillation during the passage of a train thereover and also prevent creeping of the rails and in which the movement of each rail, due to its contraction and expansion, will be limited and proportioned to the space between the two joints supporting its respective ends.

A prior patent, No. 492,848, granted to me, discloses a truss form of rail-joint provided with a flange-clamp, in which the joint is clamped to the rail by bolts passing through the clamp and through fish-plates carried thereby. The construction disclosed in such prior patent has proven disadvantageous, in that the engagement of the fish-plates with the lower surface of the rail-head prevents the flange-clamp from being adjusted to maintain it in clamping engagement with the rail-flange during the life of the joint. For example, if the fish-plates in this previous construction were made of sufficient height to engage the lower surface of the rail-head when the clamp was initially properly adjusted on the rail-flange such engagement of the fish-plates would prevent adjustment of the clamp to compensate for the working out of scale 40 and dirt from between the clamp and flange.

My present invention is an improvement over that of my former patent and provides a construction in which the adjustment of the flange-clamp is not effected by the engagement of the fish-plates with the rail-head.

In the accompanying drawings, forming a part of this application, and in which similar reference - symbols indicate corresponding parts in the several views, Figure 1 is a detail elevation illustrating my improved joint applied to a railway. Fig. 2 is a sectional view on a plane indicated by the line 2-2 of Fig. 1, and Fig. 3 is a perspective view showing my improved joint with the inclosed rail ends.

Referring to the drawings, my improved railway-rail joint is shown comprising truss-

plates A A, which are formed of sufficient strength to prevent any depression of the rail ends supported thereon. The truss-plates are provided with clamping members B B, which are constructed to engage the inclined upper surface of the rail-flange C for drawing the truss-plates against the bottom of said flange with a wedging action, whereby the flange will be securely gripped and supported. Bolts 65 G G, passing through the two truss-plates of a joint in close proximity to the lower surface of the rail-flange, provide a certain and efficient adjustment for maintaining the truss-plates securely against the lower surface of said 70 flange.

Outwardly-curved supports or fish-plates D D extend upwardly from the clamp members B B in position to be forced against the lower surface of the rail-head E by means of 75 bolts F, which latter pass through said supports and extend through the usual elongated openings in the rail-web. It will be noted that by thus constructing the supports D D with outward curvatures said supports can be 80 forced against the under surface of the rail-head E by flattening their curvature under the tension of the bolts F F. This has proven a very advantageous construction in practice, since it prevents the secure gripping action of 85 the truss-plates and clamping members on the rail-flange C from being interfered with through engagement of the supports D with the under surface of the rail-head E.

In the employment of my invention the 90 joint is properly positioned on the ends of the rails, with the end surfaces of the truss-plates extending below the top of the sleepers and abutting against the sides thereof. The bolts G are then tightened to draw the clamping 95 members into contact with the inclined upper surface of the rail-flange C, thereby forcing the truss-plates tightly against the lower surface of said flange with a wedging action. The bolts F are then tightened to force the 100 curved supports D into proper engagement with the lower surface of the rail-head E.

By placing my joint in suspended position between two sleepers I not only avoid all battering of the rail ends, such as is rendered 105 liable by improper setting in those types of joints which are supported on the tops of the sleepers, but also provide a joint which will cause any improperly-set rail ends to assume a proper position under the action of 110 passing trains.

I have found in practice that this con-

struction enables me to obtain a satisfactory and practical joint with only two clamping-bolts G, and thus to construct a short joint adapted to fit between two consecutive sleepers. Constructing the ends of the clamp with surfaces to abut against the adjacent sides of the sleepers provides a most efficient means for preventing the usual troublesome crawling of the rails, and thus obviates the necessity for constantly tightening and renewing the spikes employed for securing rails to the sleepers. It further prevents the common dragging of the joints by contraction and expansion of the rails, and thus insures that the movement of each rail, due to its expansion and contraction, will be proportioned between the joints supporting its respective ends.

Having thus described my invention, what I claim as new, and desire to secure by Letters Patent, is—

1. A rolled railway-rail joint comprising a pair of rigid truss-plates and clamp members for engaging the rail-flange, clamping means for locking said plates and members in clamped position against the rail-flange, out-

wardly - curved supports extending upwardly from said clamp members, and means independent of said clamping means for flattening the curvature of said supports to force the upper ends thereof into engagement with the lower surface of the rail-head, substantially as described. 30

2. A rolled railway-rail joint comprising rigid truss-plates constructed to engage the bottom of the rail-flange, clamp members for wedging said truss-plates against the rail-flange, clamping means for locking said plates and members in clamped position against the rail-flange, outwardly - curved supports extending upwardly from said clamp members, and means independent of said clamping means for flattening the curvature of said supports to force the upper ends thereof into engagement with the lower surface of the rail-head, substantially as described. 35 40 45

In testimony whereof I affix my signature in presence of two witnesses.

SOLOMON FINK STEVER.
